UNITED STATES PATENT OFFICE

138,302

DESIGN FOR A WOVEN TEXTILE FABRIC

John L Walther, New York, N. Y.

Application December 9, 1943, Serial No. 111,970

Term of patent 7 years

(Cl. D92—1)

To all whom it may concern:

Be it known that I, John L Walther, a citizen of the United States of America, residing in New York city, county of New York, and State of New York, have invented a new, original, and ornamental Design for a Woven Textile Fabric, of which the following is a specification, reference being had to the accompanying drawing, forming part thereof.

The figure on the drawing is a plan view of a woven textile fabric showing my new design.

The characteristic features of my design re-

side in the combination of the specific background shown with a specific stripe. The stripe is made up of a central raised portion with an equal width mottled stripe on both sides immediately adjacent thereto. The center portion contrasts to the mottled stripes and the whole stripe contrasts to the background.

I claim:

The ornamental design for a woven textile fabric, substantially as shown and described.

JOHN L WALThER.
